UNITED STATES PATENT OFFICE.

NICHOLAS LAUTERBACH, OF MERIDEN, ILLINOIS.

EXTENSION-TRUNK FOR STRAW-STACKERS.

SPECIFICATION forming part of Letters Patent No. 548,758, dated October 29, 1895.

Application filed June 14, 1894. Serial No. 514,590. (No model.)

To all whom it may concern:

Be it known that I, NICHOLAS LAUTERBACH, a citizen of the United States, residing at Meriden, in the county of La Salle and State 5 of Illinois, have invented a new and useful Extension-Trunk for Straw-Stackers, of which the following is a specification.

My invention relates to straw-stackers, and particularly to those machines adapted for 10 stacking straw and other grain during windy weather, the objects in view being to provide means whereby the trunk may be extended as the stack increases in height, to insure the 15 depositing of the straw accurately upon the top of the stack, and to avoid leaning caused by irregular formation of the stack.

Further objects and advantages of the invention will appear in the following description, and the novel features thereof will be 20 particularly pointed out in the appended claim.

In the drawings, Figure 1 is a sectional view of a stacker having a trunk constructed in accordance with my invention. Fig. 2 is 25 a plan view of the same. Fig. 3 is a view of a modified form of the stacker-trunk in which the movable section of the stacker telescopes within the main section thereof. Fig. 4 is a 30 similar view of another form of the stacker-trunk in which the movable section is arranged to fit within the main section and between the same and a guard carried by the main section. Fig. 5 is a similar view of another modified form of the stacker-trunk in 35 which an intermediate telescoping section is employed.

Similar numerals of reference indicate corresponding parts in all the figures of the drawings.

40 Fig. 1 is a partial diagrammatic representation of a thrasher to which the stacker is attached, and 2 represents a guide forming a part of the stacker and communicating with one end of the trunk 3. This trunk comprises a main 45 section 4, which is pivoted at its inner end and lower side to the guide 2 and is adapted at its upper side to slide over the rounded or arc-shaped upper side of said guide, and one or more telescoping sections 5, which are 50 adapted to be adjusted to vary the length of the trunk.

In Fig. 1 a single adjustable section 5 is fit-

ted over and receives the outer end of the main section 4, and slidably mounted upon the main section is a rack 6, connected, by 55 means of a rod 7, with the adjustable section. Meshing with this rack is a pinion 8, carried by a transverse shaft 9, to which is attached a hand-wheel 10 in convenient position for manipulation by the operator. Pivotedly connected to the outer end of the adjustable section is a hood 11, which is connected by means of an operating-rod 12 with a hand-lever 13, mounted upon the rack 6, in operative relation with a notched segment 14, formed in the 65 inner end of the rack, whereby the hood may be raised or lowered, as desired, and it will therefore be seen that the lever 13 and the segment 14 form an adjusting mechanism for the hood.

In connection with the above-described construction is the derrick 15, having a cable 16, attached to a bracket 17 on the outer end of the main section and reeled upon a drum 18, whereby the trunk may be elevated or lowered as the work proceeds.

In the form of my invention which is illustrated in Fig. 3 the construction is identical, with the exception that the outer or adjustable section is fitted within the main section, 80 and in the modified form shown in Fig. 4 the outer or adjustable section is fitted within the main section, as in Fig. 3, and attached to the main section is a tubular guard 19, which covers the inner end of the outer or adjustable 85 section and forms a shield.

In the modified form shown in Fig. 5 a plurality of outer or adjustable sections is provided, the terminal section 21 being fitted over the outer end of an intermediate section 22, which in turn is fitted over the outer end of the main section 4, and the means for operating said adjustable sections are the same as those described in connection with the form of my invention shown in Fig. 1, the rod 7, 95 which extends from the rack 6, being attached to the terminal section 21.

From the above description it will be seen that as the stack increases in height and the derrick or lifting device is operated to elevate the outer end of the trunk said trunk may be extended by turning the hand-wheel 10 to adjust the discharge-hood 11 properly over the center of the stack, and thus main-

tain a regular and properly-balanced stack. Furthermore, the arrangement of the lever for adjusting the hood upon the rack, by which the adjustable section of the trunk is extended 5 or retracted, places the means for operating all parts of the device within reach of an operator stationed at the inner end of the trunk, and, as the rack moves with the adjustable section, the connection between the hood and 10 the lever remains permanently at the same tension. Furthermore, it will be understood that in practice various changes in the form, proportion, and the minor details of construction may be resorted to without departing 15 from the spirit of the invention or sacrificing any of the advantages thereof.

Having described my invention, what I claim is—

In a pneumatic straw stacker, the combina-

tion of the main tubular trunk section, an adjustable trunk section fitted to the main section and provided at its outer end with an adjustable hood, a rack provided at one end with a rod extension attached to the adjustable trunk section and at its opposite end 25 with an adjusting mechanism, a suitably arranged pinion meshing with the rack to adjust the same, and a connection between said adjusting mechanism and the adjustable hood of the adjustable trunk section, substantially 30 as set forth.

In testimony that I claim the foregoing as my own I have hereto affixed my signature in the presence of two witnesses.

NICHOLAS LAUTERBACH.
